DISPLAY STAND FOR RUGS OR THE LIKE

Burt Hersh, Bayside, and Miles A. Godin, Flushing, N.Y.,
assignors to Joan Fabrics Corporation, Lowell, Mass.,
a Rhode Island corporation

Filed Apr. 30, 1965, Ser. No. 85,041

Term of patent 14 years

(Cl. D80—10)

FIG. 1

FIG. 3

FIG. 2

FIG. 1 is a perspective view of a display stand for rugs or the like embodying our design;

FIG. 2 is a top plan view thereof on an enlarged scale;

FIG. 3 is a side elevational view;

FIG. 4 is another side elevational view taken from a position 90° from that of FIG. 3.

The dominant features of our design reside in the portions shown in full lines.

We claim:

The ornamental design for a display stand for rugs or the like, substantially as shown and described.
